A. PFEIFER.

Emerson Reed
ATTORNEY.

UNITED STATES PATENT OFFICE.

FERDINAND A. PFEIFER, OF SPRINGFIELD, OHIO.

TOY CANNON.

Application filed October 13, 1924. Serial No. 748,310.

This invention relates to toy guns and the like and one object of the invention is to provide a toy gun, adapted to explode a paper cap or other detonating device, which will be of such a character that it can be used by a child without danger of injury to the child.

A further object of the invention is to provide a device of this kind in which the cap, or other device, will be exploded within a closed firing chamber which will prevent fire or sparks from escaping at the rear end of the gun.

A further object of the invention is to provide such a device in which the firing chamber will be self-cleaning.

A further object of the invention is to provide such a device which will be simple in its construction, easily operated and of such a character that it will not be easily broken or rendered inoperative.

Other objects of the invention will appear as the device is described in detail.

In the accompanying drawings Fig. 1 is a top plan view of a toy cannon embodying my invention; Fig. 2 is a longitudinal sectional view of the same; Fig. 3 is a rear elevation of the same; and Fig. 4 is a section taken on the line 4—4 of Fig. 2.

In these drawings I have illustrated one embodiment of my invention and have shown the same as embodied in a toy cannon but it will be understood that this particular embodiment has been chosen for the purpose of illustration only and that the invention may be applied to toy guns of various kinds and may take various forms.

As here shown, the gun comprises a barrel 1 formed in imitation of a cannon and mounted on the axle 2 of a supporting truck which, in the present instance, is provided with wheels 3. Rigidly connected with the barrel and extending rearwardly and downwardly therefrom is a supporting member 5. The rear portion of which will rest upon the ground and support the barrel in its proper position. The barrel is provided with a longitudinal bore 6 which opens through the front end or muzzle of the gun and the rear portion of which is enlarged, as shown at 7, to form a firing chamber. Mounted within the firing chamber, near the rear end thereof, is a firing block or anvil 8 which is rigidly mounted and may, if desired, be cast integral

with the barrel. The rear end of the firing chamber is closed by an end wall 9 which, however, is provided with an opening 10 which extends through the lower portion of the rear wall and through the lower wall of the barrel in the rear of the firing block and the barrel is also provided with a second opening 11 which extends through the lower wall thereof immediately in front of the firing block. Side plates or lugs 12 extend downwardly from the barrel on opposite sides of the openings 10 and 11 and have mounted between them a hammer 13, this hammer being preferably mounted on a pin 14 which extends through the lugs 12. The hammer is of a thickness substantially equal to the width of the space between the lugs 12, there being just sufficient clearance to permit of the free movement of the hammer about its axis. The hammer is provided on its upper and forward side with a face 15 adapted to support a cap, or other device which is to be exploded, and to move the same into contact with the firing block, thereby causing it to be exploded. At the lower end of this cap supporting face the hammer is provided with a forwardly extending portion 16 which forms a shoulder to limit the inward movement of the cap when the latter is inserted through the opening 10 and placed in position on the supporting surface, thereby insuring the proper positioning of the cap with relation to the anvil. This forward extension or shoulder 16 is of such a length that when the hammer is in its retracted position, as shown in Fig. 2, the shoulder will extend from the firing face 15 of the hammer to the firing block, thus forming a bottom for the opening 10 which will prevent the cap from falling through the opening. The outer portion of the hammer, below the firing face 15, is of such a width that when the firing face is moved into contact with the firing block this outer portion of the hammer will completely close the opening 10 and, inasmuch as the hammer fits snugly between the lugs 12, it will be obvious that the rear end of the gun will be completely closed and that neither sparks nor ignited pieces of the paper cap can escape therefrom. When the paper cap is exploded against the firing block, portions of the cap will remain on the hammer while other portions will enter the firing chamber

and will be carried forward beyond the firing block. These pieces of the cap will find their way through the opening 11 and be discharged from the firing chamber. The shoulder 16 of the hammer is of such a length that when the face 15 of the hammer is in engagement with the firing block the shoulder will extend entirely across and will close the opening 11. Consequently this opening is also closed at the time the cap is exploded. This results not only in positively preventing the escape of sparks or pieces of the exploded device at the rear of the gun but also forces the smoke to travel lengthwise of the barrel and escape through the muzzle thereof, after the manner of an ordinary cannon.

The hammer may be actuated in any suitable manner but preferably it is spring operated and is normally held in its retracted position by releasable means which, when released, will permit it to be forced against the firing block by the action of the spring. As here shown, the hammer is provided with a downwardly extending finger or cam shaped portion 17 having a narrow lower end which bears upon the free end of a flat spring 18 which is supported near its rear end on a pin 19 and has its rear end extending beneath a cross bar 20 on the part 5 of the gun. The arrangement of the finger 17 with relation to the spring 18 is such that when the hammer is in its retracted position, as shown in Fig. 2, the pressure of the spring on the finger will be forward, thus causing the hammer to be retained in its retracted position. When the finger is moved slightly to the rear the line of pressure shifts and tends to move the finger rearwardly, thus forcing the hammer against the firing block. The hammer is provided with a finger piece 21 by means of which it may be retracted against the tension of the spring and when so retracted will be held in this position until the hammer is positively actuated to release the same. This releasing movement may be imparted to the hammer in any suitable manner but, in the present instance, the hammer has an arm 22 extending below the spring 18 and constituting a trigger to which pressure may be applied to impart initial movement to the hammer. Preferably a suitable lanyard, such as a cord 23, is connected with the arm 22 and extends rearwardly to a point some distance from the barrel of the gun so that the gun may be fired without the necessity of placing the hand near the firing chamber or hammer.

It will be apparent from the foregoing description that I have provided a toy gun by means of which paper caps or the like may be exploded with safety; which is simple in its construction and operation and may be fired from a remote point; that the

firing chamber is self-cleaning and will not become clogged with pieces of the exploded caps and that all openings at the breech of the gun are fully closed when the cap is exploded.

70

While I have shown and described one embodiment of my invention, I wish it to be understood that I do not desire to be limited to the details thereof as various modifications may occur to a person skilled in the art.

75

Having now fully described my invention, what I claim as new and desire to secure by Letters Patent, is:

1. A toy gun comprising a barrel having a firing chamber provided with an opening through the rear wall therof, a firing block arranged within said chamber in front of said opening, said barrel having an opening between said firing block and the first mentioned opening to connect the firing chamber with said barrel, a hammer having a part to support the device which is to be exploded and move the same into contact with the firing block, said part of said hammer being arranged to close the first mentioned opening before it engages the firing block, and means for actuating said hammer.

80

2. A toy gun comprising a barrel having a firing chamber provided with an opening through the rear wall therof, a firing block arranged within said chamber in front of said opening, a hammer mounted within said firing chamber and having a part arranged to be moved into line with said opening to receive the device which is to be exploded, and means for actuating said hammer to cause said device to be moved into contact with said firing block.

85

3. A toy gun comprising a barrel having a firing chamber and having an opening at the rear end thereof, a firing block mounted within said chamber in front of said opening, a hammer within said firing chamber, pivotally mounted beneath said firing block and having a part arranged to be moved into line with said opening to receive the device which is to be exploded and to move said device against said firing block, said hammer being arranged to close said opening before said device engages said firing block, a spring for actuating said hammer, and means for controlling the action of said spring on said hammer.

90

4. A toy gun comprising a barrel having a firing chamber provided with parallel side walls and having an opening at the rear end thereof and below the top wall of said firing chamber, a firing block arranged between said side walls in front of said opening, a hammer having a part fitting closely between said side walls and movable into contact with said firing block, said part of said hammer being arranged to pass the upper

130

edge of said opening and close the same before said part engages said firing block, and means for actuating said hammer.

5. A toy gun comprising a barrel having a firing chamber, a firing block arranged within said firing chamber, said barrel having an opening through the lower portion of the rear wall of said firing chamber and having parts extending downwardly on the 10 opposite sides of said opening, a hammer pivotally mounted between said parts and substantially filling the space between the same, said hammer having a part movable into contact with said firing block and so arranged that when said hammer is in its retracted position said part will be in line with said opening to receive and support the device which is to be exploded, a spring for actuating said hammer, and means for 15 controlling the operation of said hammer by said spring.

6. A toy gun comprising a barrel having a firing chamber provided with an opening at the rear end thereof, a firing block arranged within said firing chamber adjacent to said opening, said barrel having parts extending therefrom on opposite sides of said opening, a hammer pivotally mounted between said parts and having a supporting face to receive the device to be exploded and having at the inner end of said face a shoulder to position said device on said supporting face, and means for actuating said hammer to move said device against said firing 20 block.

35 7. A toy gun comprising a barrel having a firing chamber, a firing block arranged within said firing chamber, said firing chamber having openings through the wall thereof, both in the rear and in the front of said firing block, a hammer pivotally mounted beneath said firing block and having a supporting face to receive the device to be exploded and having parts arranged to close 40 both of said openings before said device is moved into engagement with said firing block, and means to actuate said hammer.

50 8. A toy gun comprising a barrel having a firing chamber provided with an opening through the lower portion of the rear wall thereof, a firing block mounted within said firing chamber in advance of said opening, said barrel having a second opening through the lower wall thereof immediately in advance of said firing block, said barrel also 55 having parts extending downwardly from the opposite sides of said openings, a ham-

mer pivotally mounted on said parts and substantially filling the space between the same, the rear portion of said hammer having a cap supporting face and being of such width that when said face is moved into contact with said firing block said part of said hammer will completely close the first mentioned opening, said hammer also having a 60 65 part extending upwardly and forwardly from the inner edge of said supporting face to position the cap on said face, said upwardly and forwardly extending part being of such length that it will be moved across 70 and will close the last-mentioned opening before the supporting face is moved into operative relation to said firing block, and means for actuating said hammer.

9. A toy gun having a firing chamber, a firing block arranged within said chamber, a pivoted hammer having a part movable into engagement with said firing block, said hammer also having a finger projecting from that side thereof opposite said firing block, 75 and a flat spring having a smooth upper surface engaging the end of said finger, said finger being so arranged with relation to said spring that when said hammer has been retracted the pressure of the spring on the finger will be in a direction to retain the hammer in its retracted position and after initial movement has been imparted to said hammer the pressure of said spring on said finger will be in a direction to move said 80 85 hammer toward the firing block.

10. A toy gun having a firing chamber, a firing block arranged within said chamber, a pivoted hammer having a part movable into engagement with said firing block, said 90 95 hammer also having a finger projecting from that side thereof opposite said firing block, and a flat spring having a smooth upper surface engaging the end of said finger, said finger being so arranged with relation to said spring that when said hammer has been retracted the pressure of the spring on the finger will be in a direction to retain the hammer in its retracted position and after initial movement has been imparted to 100 105 said hammer the pressure of said spring on said finger will be in a direction to move said hammer toward the firing block, said hammer also having an arm for imparting initial movement thereto, and means for actuating said arm.

In testimony whereof, I affix my signature hereto.

FERDINAND A. PFEIFER.
